H. OSSWALD

POWER PRESS

Filed Jan. 6, 1925

UNITED STATES PATENT OFFICE.

HERMAN OSSWALD, OF NIVERVILLE, NEW YORK, ASSIGNOR TO THE V & O PRESS COMPANY, OF HUDSON, NEW YORK, A CORPORATION OF NEW YORK.

POWER PRESS.

Application filed January 6, 1925. Serial No. 925.

This invention relates to an improvement in power presses for cutting and forming sheet metal and other material, with the object in view of increasing the efficiency and durability of the press.

Another object is to provide means for intermittently actuating the brake.

Another object is to provide means for releasing the brake, which means coacts with the clutch mechanism, so that the load or frictional contact of the brake may be removed from the shaft before the clutch mechanism engages the power applying means.

15 The type of power press to which my present invention is applied, is shown, described and claimed in Letters Patent No. 769,955, dated September 13th, 1904, in which means are disclosed for locking the operating shaft to the drive wheel by the laterally movable clutch dog, and in Letters Patent No. 880,239, dated February 25th, 1908, in which means are illustrated for preventing the locking of the operating shaft to the drive wheel for more than a single revolution of the operating shaft in the event the operator should keep the shaft controlling treadle depressed a longer time than is necessary.

30 The clutch mechanism including the latch and switch plate, with which my present invention coacts, is shown, described and claimed in my copending application, Serial No. 723,023, filed June 24th, 1924.

35 A practical embodiment of my invention is represented in the accompanying drawings, in which—

Fig. 1 represents a side elevation of a power press of well known construction, partly in section, showing the parts in the position they assume when the drive wheel and operating shaft are locked by the clutch dog, the switch plate withdrawn by the treadle connection and the brake released from the shaft.

Fig. 2 represents on a larger scale a detail section of the mechanism adjacent the brake and coacting therewith.

50 Fig. 3 represents a similar view with the parts in the position shown in Fig. 1, and

Fig. 4 represents a detail vertical section

taken in the plane of the line IV—IV of Fig. 2.

The pedestal of the press is denoted by 1, the frame by 2, in which frame the drive wheel 3 and the operating shaft 4 are mounted. The shaft 4 is arranged to be clutched to the drive wheel by the spring pressed clutch dog 5 which is moved into engagement with the drive wheel by its spring (not shown) 55 when the dog is released by the outward movement of the switch plate 6, which switch plate is slidably mounted in its guide frame 7 and yieldingly held at the limit of its inward movement by the usual springs 8 60 shown in the dotted outline in Figs. 2 and 3, for holding the clutch dog released.

The treadle 9, which is pivoted at 10 to the pedestal 1, is yieldingly held at the limit of its raised position by the spring 11. This 70 treadle is connected by a rod 12 to a rock arm 13 pivoted at 14 to the frame 2.

A latch 15 is pivoted at 16 to the rock arm 13, the hooked end of which latch is arranged to be engaged with and disengaged 75 from an abutment 17 on the switch plate 6. This latch 15 is yieldingly pressed toward the abutment 17 by a spring actuated presser pin 18.

A latch releasing lever is pivotally 80 mounted on an eccentric bushing 19, one arm 20 of which lever engages the operating shaft 4 within a circumferential groove 21 in said shaft, across which groove the spring pressed clutch dog 5 extends. The other 85 arm 22 of the latch releasing lever engages a cam surface 23 on the latch 15.

The eccentric bushing 19 is rotatively mounted on the shank of a screw bolt 24, which screw bolt may be tightened to clamp 90 the bushing in its rotatively adjusted position.

It will be understood that when the switch plate 6 is withdrawn from the latch 15, the clutch dog is moved by its spring to clutch the shaft to the drive wheel and at the same time it will form an abutment in the said groove 21, so that as the shaft rotates the portion of the clutch dog located within the groove will come into engagement with the 95 arm 20 of the latch operating lever and swing it outwardly, thereby moving the arm 100

22 of the lever inwardly to release the latch from its engagement with the switch plate and permit the switch plate to be moved inwardly by its springs to slide the clutch dog 5 out of its locking engagement with the drive wheel and thereby disconnect the operating shaft therefrom.

The mechanisms above described are substantially illustrated and described in United States Letters Patent No. 880,239, and my copending application, Serial No. 723,023, hereinbefore referred to and a specific description of their operation will therefore be unnecessary, the present invention being directed to the novel adjustable brake releasing device for removing the frictional contact from the operating shaft at the time the switch plate is being withdrawn to release the clutch dog, which device is constructed, 20 arranged and operated as follows:

The enlarged portion 25 of the shaft 4 is arranged to be embraced by elements 26, 27 which form the contact members of the brake. The element 26 is secured to the 25 guide frame 7 by means of bolts 26*, and serves as a cover for the switch plate 6, and the element 27 is hinged at 28 to the element 26. These elements 26, 27 are provided with lugs 29, 30 respectively, which lugs are arranged to receive a bolt 31, the head 32 of which engages the lug 30 of the movable element 27, while the threaded end of the shank extends through the lugs and has a nut 34 between which and the lug 29 a spring 35 is disposed. The tension of the spring 35 between the lug 29 and nut 34 tends to normally hold the elements 26, 27 in contact with the enlarged portion 25 of the shaft 4, thereby placing a frictional drag on the 40 shaft. In order to release this frictional contact of the shaft 4, I provide an arm 36 pivoted at 37 and having a laterally projecting end 38, which extends into the path of the switch plate 6. The upper end of the 45 arm 36 is arranged to receive a bolt 39 which is adjustably secured therein and adapted to engage the end of the bolt 31. Thus it will be seen that as the foot of the operator actuates the treadle to withdraw the switch 50 plate 6 and permit the clutch dog to move toward the drive wheel 3, the switch plate will engage the laterally projecting end 38 of the lever 36 and move it so as to cause the bolt 39 to contact with the bolt 31 and 55 compress the spring 35 between the lug 29 and nut 34. As the bolt 31 is moved in the lugs 29, 30 the movable element 27 is permitted to swing on its pivot 28 away from the enlarged portion 25 thereby permitting 60 the shaft 4 to rotate freely. When it is desired to stop the press, the switch plate 6, by reason of its actuating spring, will, when the dog 5 is brought around into position, move inwardly and cause the dog to be slid 65 out of its locking position with the drive

wheel 3. Simultaneously with the movement of the switch plate 6 the lever 36 will be rocked and the bolt 39 returned to its normal position, thus relieving the additional tension on the spring 35 and permitting it to exert its pressure on the head of the bolt and lugs 29, 30 of the elements 26, 27, which are again brought into frictional contact with the enlarged portion 25 of the shaft 4.

75 From the foregoing it will be seen that I have provided a very simple and effective device for intermittently releasing the brake on the shaft 4 thereby relieving the constant frictional drag on the shaft and increasing 80 the efficiency and durability of the press.

85 It is evident that various changes may be resorted to in the construction, form and arrangement of the several parts without departing from the spirit and scope of my invention; hence, I do not wish to be limited to the particular embodiment herein shown and described, except as they may be included in the claims.

90 What I claim is:—

1. In a power press, the combination with the drive wheel, the operating shaft and the clutch mechanism, of a brake normally engaging the shaft, and means operated by the initial movement of the clutch mechanism 95 for releasing said brake in advance of the clutch, whereby the action of the brake on the shaft is removed before the clutch mechanism coacts with the shaft.

2. In a power press, the combination with the drive wheel, the operating shaft and the clutch mechanism, of a brake normally engaging the shaft, and means comprising an arm operated by the initial movement of the clutch mechanism for releasing said brake 100 in advance of the clutch, whereby the action of the brake on the shaft is removed before the clutch mechanism coacts with the shaft.

3. In a power press, the combination with the drive wheel, the operating shaft and 110 the clutch mechanism, of a brake normally engaging the shaft, and means comprising an arm operated by the movement of the clutch mechanism for releasing said brake, 115 said arm having an adjustable brake contact member.

4. In a power press, the combination with the drive wheel, the operating shaft and the clutch mechanism, of a brake normally engaging the shaft, said brake comprising a 120 fixed element, a movable element and a spring actuated device engaging said elements, and means operated by the movement of the clutch mechanism arranged to engage said device for releasing the brake.

125 5. In a power press, the combination with the drive wheel, the operating shaft and the clutch mechanism, of a brake normally engaging the shaft, said brake comprising a 130 fixed element, a movable element and a

spring actuated device engaging said elements, and means comprising an arm operated by the movement of the clutch mechanism arranged to engage said device for releasing the brake.

6. In a power press, the combination with the drive wheel, the operating shaft and the clutch mechanism, of a brake normally engaging the shaft, said brake comprising a fixed element, a movable element and a

spring actuated device engaging said elements, and means comprising an arm, said arm having an adjustable contact member arranged to engage said device for releasing the brake.

15

In testimony, that I claim the foregoing as my invention, I have signed my name this 16th day of December, 1924.

HERMAN OSSWALD.
